(57) **CLAIM**

The ornamental design for a ball, as shown and described.

DESCRIPTION

FIG. 1 is a top perspective view of the ball.

FIG. 2 is a front elevation view of the ball.

FIG. 3 is a back elevation view of the ball.

FIG. 4 is a top plan view of the ball.

FIG. 5 is a bottom plan view of the ball.

FIG. 6 is a left side elevation view of the ball.

FIG. 7 is a right side elevation view of the ball; and, FIG. 8 is an elevation section view of the ball taken along line 8-8 in FIG. 2.

The broken lines illustrate the plane upon which a sectional view is taken and form no part of the claimed design.
